ABSTRACT: The isolating switch employs semispherical-type electrode shielding energized parts which are mounted on the top of a pair of tilted insulator columns. The columns are mounted to a support frame by means of rotor bearings, which, when rotated by an appropriate mechanism, cause the tops of the insulator columns to move in a circular path. Linkages are employed and are responsive to column rotation in a first direction to electrically contact the blade and jaw of the switch arrangement, and to withdraw the blade and jaw in response to column rotation in a second direction to break contact. The smooth surfaces of the electrodes employed face one another in this second instance and provide an open gap condition which produces a substantially uniform electrostatic field between facing surfaces.

ISOLATING SWITCH FOR A HIGH-POWER ELECTRICAL DISTRIBUTION SYSTEM

BACKGROUND OF THE INVENTION

This invention relates to electrical power transmission and distribution systems, and, more particularly, to a novel insulating switch employed therein.

With the growth of the electrical power industry, transmission voltages have increased from modest values of 5 to 15 kv. to the present high levels of 500 to 750 kv. As further growth in the industry occurs, it is anticipated that transmission voltages will extend to 1,000 to 1,500 kv. In the development towards these higher voltages, it has been recognized that a new concept in switch design is imperative due to the increasing necessity to shield the energized switch parts at these higher potentials.

It is an object of the present invention to provide a new and improved isolating switch for use at such ultra-high voltages, which provides shielding for the contact members of the switch when the switch is in closed position.

It is another object of the invention to provide such an isolating switch which enables the establishment of an open gap of limited dimensions.

It is a further object of the invention to provide an isolating switch whose overall length is kept reasonably small.

It is yet another object of the invention to provide such a switch wherein the contact members of the switch are also shielded when the switch is in the open position.

It is also an object of the invention to provide an isolating switch for use at ultra-high voltages wherein dielectric stress is kept reasonably small.

These and other objects of the invention will be more fully understood from a consideration of the following description taken in connection with the drawings in which:

FIG. 1 shows a front elevational view of an isolating switch constructed in accordance with the invention;

FIG. 2 shows a plan view of the isolating switch of FIG. 1; and

FIG. 3 shows a perspective view illustrating the use of the isolating switch in a substation environment.

As will become clear hereinafter, it will be seen that such an isolating switch employs semispherical electrode shielding over the energized parts of the switch. These parts are mounted on the top of a pair of tilted insulator columns which are, in turn, mounted on rotor bearings connecting the insulator columns to a support frame. As the rotor bearings are controlled by appropriate means to open and close the switch, the tops of the insulator columns are caused to move along a circular path. By means of linkages incorporated within the switch, circular movement in one direction causes engagement of the switch blade and a cooperating jaw to connect one power line to another. This closed position of the switch is to be contrasted with the open position, caused by circular movement in an opposite direction, whereby the linkages serve to retract the blade and jaw into their respective electrodes and to break the connection. At the same time, this latter movement is such as to present the substantially smooth surfaces of the electrodes employed towards one another to establish an open gap position of a length substantially less than has heretofore been experienced with rod gap arrangements in prior isolating switch designs. Such smooth gap conditions are more fully disclosed in pending applications Ser. No. 681,743, filed Nov. 9, 1967, and Ser. No. 839,456, filed July 7, 1969, both assigned to the same assignee as the instant application.

DESCRIPTION OF THE INVENTION

As is well known, disconnecting switches are designed to isolate electrical apparatus and portions of electrical systems from energized lines for safe handling, maintenance, repair and inspection. It is, therefore, most important to provide adequate protection for personnel working in the immediate region of the disconnected equipment. Hence, when the

switch is open, it is necessary that the gap in the open position be adequate to withstand all usual, as well as unusual, voltages which are impressed upon it by the system. If the surge voltage causes the switch open gap to flash over, the lives of personnel may be placed in serious jeopardy.

Such disconnecting switches are customarily designed so that the switch open gap will withstand higher voltages than the insulator columns which support the energized parts from the grounded metal base. As a result, flashover is much more likely to occur between the energized parts and ground, rather than across the switch open gap. In this manner, the insulator columns provide protection for the switch and operating personnel against switching surge voltages and impulse voltages. However, this requires the provision of very large open gaps in the switch to insure greater insulation strength or withstand than exists across the insulator columns.

In the past, disconnecting switches have been constructed with large open gaps and having nonuniform electric field distribution due to the geometry of the switch blade and associated contacts. In some instances, methods were provided to reduce the insulation strength of the insulator columns to insure higher insulation strength across the open gap than existed down the insulator columns to earth. These methods have included the use of devices such as rod electrodes connected to the base of the insulator columns. These methods, however, suffered from the drawback that the effective insulation strength or withstand of the insulator column cannot be reduced without limitation. Also present was the additional drawback that the gap between the switch blades of the disconnecting switches establishes the insulating distances as essentially that between rod electrodes, and since the withstand of the insulator column must always be sufficiently high, this gap must of necessity remain large.

If these problems weren't enough in the present transmission systems of 500 to 700 kv. the problems become more difficult to overcome in future transmission systems using voltages as high as 1,000-1,500 kv. These systems require disconnecting switches having insulator columns with sufficient voltage withstand. The insulator columns preferably should be of the order of 20 feet or so to provide adequate withstand for switching surges of 2,300 kv., or more. Under these conditions, it will be readily apparent that the switch open gap using existing switch blade arrangements must be considerably longer (e.g., 25-30 feet) to ensure that flashover will be down the insulator column rather than across the open gap.

As will now become clear, the present invention provides a new and novel isolating switch whereby the switch open gap is substantially shortened to produce greater control of any flashovers without the necessity of reducing the effective withstand of the insulator columns. This invention also permits the use of shorter switch blades and a shorter mounting base to effect a substantial saving; and, especially in situations where the withstand of the insulator column is not required to be high under operating conditions, these components may be shortened even further. The invention also permits a substantial savings in yard space as a result of the use of shorter switch blades and shorter switch open gaps. It has been found that a substantially uniform electrostatic field is produced between the facing surfaces of the electrodes employed in this arrangement.

Referring now to FIGS. 1 and 2, there is shown a two insulator disconnect switch assembly comprised of a supported switch base 10 which is preferably of a rigid, metallic structure. The switch base 10 is electrically grounded by a suitable conductor (not shown). The switch base 10 is provided with rotor bearings 12 which secure the lower portions of the insulator columns 14, 14a in any desireable manner such that the insulator columns can rotate with respect to base 10. As shown in the drawings, insulator columns 14, 14a are tilted at an angle of some 30° with respect to the base 10.

The opposite ends of the insulator columns 14, 14a cooperate to support a pair of metallic electrodes and a retractable switch blade. In particular, the insulator columns

14, 14a rigidly support a pair of spherical electrodes 16, 18, each of which is slotted along the length thereof. A pair of switch blades or contact arms 20, 22 are positioned to be extendable through the slots of electrodes 16, 18, respectively, when the switch is in the closed position. Switch blades 20, 22 are each made of suitable conductive material so as to provide an efficient and continuous conductive path when connected in electrical circuit.

Although not specifically shown as such for purposes of simplification, switch blade 20 has a projecting beavertail at its contact end to cooperatively engage with the contacts 26 and 28 of the jaw 30 of the switch blade 22. Conductors 32 and 34 are respectively coupled to switch blade elements 20 and 22 in this and other environments, in any suitable manner, and connect these components to suitable utilization apparatus (not shown). It is to be noted that while spherical electrodes have been shown, the electrodes 16 and 18 may also be generally shaped toroidal rings, ellipsoids or spheroids. In the arrangement of FIGS. 1 and 2, the slotting of the electrodes 16, 18 effectively provide a semispherical shielding over the energized parts 20, 22.

The retractable blades 20 and 22 for alternately closing and opening the disconnect switch are shown as being in alignment in the plane formed by the openings in the two spherical electrodes 16, 18. These blades are operated to slide within the opening and to make electrical contact between them when the switch is desired to be closed. When the switch is to be opened, the blades 20 and 22 are arranged to wholly retract within their respective electrodes. Such opening and closing action is governed by pairs of castings 36, 36a, shafts 38, 38a and linkages 40, 40a, with one of each pair being associated with electrodes 16 and 18, respectively.

As will be seen from the drawings, casting 36 couples the top of the insulator column 14 to the electrode 16 and casting 36a couples the top of insulator column 14a to the electrode 18. Each casting is shown to project in a direction towards the center of rotation of the rotor bearing 12. Shaft 38 is attached to the end of casting 36 at a point in alignment with the center of rotation of the left hand rotor bearing 12, and is employed to support the conductor 32. Shaft 38a, similarly, is attached to the end of casting 36a at a point in alignment with the center of rotation of the right-hand rotor bearing 12, and supports the conductor 34. Since the shafts 38 and 38a effectively are in coaxial alignment with the rotor bearings 12, they will rotate in a manner similar to that of the rotor bearings. Also, it will be noted that no horizontal movement of the shafts 38 and 38a will take place, so that the ends of conductors 32 and 34 will remain in a substantially horizontal position. As will be appreciated, rotation of the bearings 12 can be effected by a conventional gear device (100 in FIG. 3), such as a motorized gear box supported by the switch base 10.

The previous description has been with the understanding that the rotor bearings 12 have been moved to position the spherical electrodes 16 and 18 in the position shown in FIG. 1 and in solid lines in FIG. 2. This basically represents the closed position of the disconnect switch, with a complete electrical circuit path being established between conductors 32 and 34. The following description is directed towards the retraction of the switch blades 20, 22 within their respective spherical electrodes 16, 18 to open the switch connection.

As will be evident to one skilled in the art, movement of the rotor bearings 12 serves to rotate the upper ends of insulator columns 14, 14a in a circular pattern. Because of the connections between insulator columns 14, 14a and castings 36, 36a, this movement of the rotor bearings 12 also effects circular movement of the spherical electrodes 16, 18 in a horizontal plane. Since the center of rotation of the rotor bearings is in alignment with shaft 38, on the one hand, and with shaft 38a, on the other hand, the circular movement will be about these shafts. This rotation is illustrated by the dotted configuration of the electrodes 16', 18' in FIG. 2.

By virtue of the linkage arrangements 40 and 40a joining a pin on the casting 36 and 36a to respective switch blades 20, 75

22, the circular rotation of the rotor bearing 12 not only serves to move the electrodes 16 and 18 in a circular path, but also serves to retract the switch blades 20 and 22 wholly within the electrodes when in the positions shown by representations 16', 18'.

5 In this open position of the switch, only the substantially smooth surfaces of the spherical electrodes 16', 18' face one another, to provide open gap region. As described in the aforementioned pending applications Ser. No. 681,743 and Ser. No. 839,456, such an open gap between substantially smooth surfaces can be much less than open gap distances between rod electrodes, while continuing to insure that any 10 flashover will be down the insulator column instead of across the open gap. In this manner, it will be seen that the use of the spherical electrodes permits an open gap of limited dimensions and, therefore, enables the overall lengths of the disconnect switch to be kept small, even for the ultra-high high voltage environments transmitting 1000 to 1500 kv. voltages.

Other advantages are present with the disconnect switch 15 described herein. Thus, it will be seen that the spherical electrodes 16, 18 provide shielding for the retractable switch blades 20, 22 both when the switch is closed and when the switch is in the open position. Safety is thus maintained throughout the usage of the switch in transmitting electrical power and when disconnecting the switch to provide the maintenance and repair function. It will also be noted that indentations (such as 42, 42a) can be provided in the lower portions 20 of the spherical electrodes 16, 18, to shield the upper portions of the insulator columns 14, 14a so as to reduce dielectric stress. This latter feature is easily attainable with the present design, and is much simpler than characterized by prior switch arrangements where proper dielectric requirements were had only by increasing switch dimensions as voltages increased.

25 A perspective view illustrating the relative dimensions of 30 the component parts of the isolating switch mechanism as it might be used in a three phase substation environment is shown in FIG. 3.

35 While there has been described what is considered to be a preferred embodiment of the present invention, it will be appreciated that further modifications are feasible, not only through the use of employing toroidal rings, ellipsoids or spheroids as described above. Other similar arrangements are well within the scope of the present invention, and fall within the 40 scope of the claims as defined below.

45 I claim:

1. An electric switch comprising:
first and second spaced apart hollow electrodes operative to produce a substantially uniform electrostatic field between facing surfaces thereof when in a disengaged switch position, with each such electrode having a longitudinally aligned slotted portion;
first and second retractable switch blades respectively mounted within said electrodes;
first and second means operative to respectively rotate said first and second electrodes in a first direction to align the slotted portions thereof when switch engagement is desired and to rotate said electrodes and said slotted portions in a second direction away from one another when switch disengagement is desired;
mechanical linkage means each cooperating with an associated one of said electrodes and respectively coupled to one of said first and second means to move said first and second switch blades along linear paths so as to protrude through said slotted portions to make electrical contact therebetween when said electrodes rotate to the engaged switch position and to retract said switch blades within said slotted portions and along said linear paths as said switch blades rotate in paths transverse to said linear paths to break said electrical contact when in said disengaged switch position;
first and second conductors having terminals extending into said electrodes for coupling said switch into an electrical circuit;

first and second pivot connections respectively positioned within said first and second electrodes for coupling their associated switch blade to one of said conductors; said first and second means each being coupled to said mechanical linkages and said electrodes at a point spaced from its associated pivot connection for rotating said electrodes about their respective pivot connections.

2. An electric switch as defined in claim 1 wherein said first and second electrodes comprise a pair of spherical shaped hollow electrodes operative to produce a substantially uniform electrostatic field therebetween when in a disengaged switch position to thereby shield both the terminals and the switchblades.

3. An electric switch as defined in claim 1 wherein said first and second electrodes comprise a pair of spherical electrodes mounted on first and second insulator columns, respectively, and wherein said insulator columns are supported by an electrically grounded base.

4. An electric switch as defined in claim 3 wherein said first and second means includes said first and second insulator columns and a mechanism for simultaneously rotating said columns such that the mounting of said columns to said electrodes is operative to produce a rotation of said electrodes in a horizontal plane in a circular path in response to excitation of said mechanism.

5. An electric switch as defined in claim 4 wherein said mechanical linkage means includes a linkage system coupled between said first member of each electrode-insulator column arrangement and its associated retractable switch blade for projecting and retracting said switch blade within its respective electrode under excitation of said mechanism.

6. An electric switch as defined in claim 5 wherein said insulator columns are each oriented in a vertical plane with respect to the grounded electrical base, but tilted towards the horizontal from an upright vertical position.

7. An electric switch as defined in claim 6 wherein the undersides of said spherical electrode are indented to reduce

dielectric stress.

8. An electric switch as defined in claim 6 wherein said first retractable switch blade includes a projecting beavertail at its contact end and said second retractable switch blade has a jaw contact at its corresponding end to cooperatively move into sidewise engagement with said first switch blade in the engaged switch position.

9. A switch comprising:

a support;
first and second diagonally aligned insulators;
first and second means for rotatably mounting the lower ends of said insulators upon said support;
a pair of hollow slotted metallic shells;
a pair of conductors each having end terminals extending into the interiors of said shells;
first and second slidably engageable switch blades each positioned within an associated shell;
first and second pivot connections respectively coupling each end terminal to an associated one of said switchblades;
first and second arms positioned within said shells and secured to the upper ends of said insulators and to the undersides of their respective shells at points removed from said pivot connections for rotating said shells about respective imaginary lines extending between a pivot connection and an associated one of said first and second means.

10. The switch of claim 9 further comprising:

first and second mechanical linkages each coupled between one of said first and second arms and its associated switchblade for linearly moving their switch blades out of said shells and into engagement when said switch is in the closed position and for withdrawing their associated switchblades into their associated shells when said switch is in the open position whereby said shields provide dielectric shielding for their associated switchblades and conductor terminals.
